REPRODUCING MAGNET FOR TELEGRAPHONES

Application filed April 12, 1929, Serial No. 354,684, and in Germany September 26, 1928.

It is known that sound records can be electromagnetically fixed on a steel wire and be reproduced. For this purpose, use is made of small magnets which are conveniently assembled in a small casing in such a manner that the fine steel wire can pass through the said casing, entering through a narrow slot, passing along the magnet cores and then leaving the casing again through a narrow slot. 5 This device may be referred to as a "talking head". These talking heads are so constructed that all the passages are kept very narrow in order to permit a passage of the wire free of any vibrations. If the wire had for instance 10 a thickened part it could not pass through the said talking heads. Now, such record wires have recently been successfully used as a musical accompaniment for moving pictures and generally employed as the acoustic 15 part of the so-called talking film. If such a wire is used in a talking film it must be possible to cut it up in exactly the same way as the pictorial part of a film, so that if the pictorial part contains damaged parts which 20 have to be cut off, the corresponding parts of the sound record wire may also be cut off in order that the picture and the sound may be synchronized. However, this would not be possible with the talking heads as now 25 used, since the thickened part at the ends of the wire which are produced by the riveting or welding together of the wire ends could not pass through the normal talking head. 30

The object of the present invention is to 35 produce a talking head which will allow such thickened wire produced by riveting or welding to pass through.

The inlet-end of the talking head is funnel-shaped and is closed by two movable jaws. 40 When the riveted or welded portion of the wire passes along the said jaws, the latter yield, and by means of a small lever arrangement allow the small magnets of the talking head to return quickly into their position. 45 Movable jaws are also arranged at the outlet end of the wire, which movable jaws release a locking device, thereby effecting a rapid return of the small electro-magnets into their normal position.

50 Obviously other forms of construction may

be employed which will produce the same effect, that is to say, that the two halves of the talking head will as a whole recede when the thickened part of the wire passes through. The essence of this invention consists in this, 55 that a talking head is employed which allows thickened portions of the wire to pass through without any disturbance in the operation, which has not been possible with the talking heads as hitherto employed. 60

One form of carrying the invention into effect is illustrated by way of example in the accompanying drawings, in which,

Figure 1 illustrates a horizontal section of the talking head when the wire passes 65 through it, Figure 2 showing the same in elevation, when a thickened portion of the wire passes through.

Figure 3 is an end view of the talking head corresponding to the position shown in Figure 1, whilst

Figure 4 illustrates an end view corresponding to the position shown in Figure 2. The wire 2 with the thickened points 1 passes through a two-part casing formed by 70 two plates, 3 and 4, and containing the magnets 5 and 6 for the magnetization of the wire. The guiding of the wire is effected along corresponding grooved guiding members 7 and 8, which are constituted by discs 75 provided with recesses 9 and 10, the journals 7', 7'', 8', 8'' of the discs being formed with screw threads running in opposite directions. The said screw threaded journals engage in corresponding screw threaded 80 counterparts formed in the plates 3 and 4. When the discs 7 and 8 are rotated in opposite directions, the plates 3 and 4 must either approach or recede from one another. The discs 7 and 8 are coupled together to rotate 85 in opposite directions, this being effected by means of toothed segments 11 and 12 which are mounted on the screw threaded journals 7'' and 8'' respectively. If a thickened part 90 1 of the wire runs towards the left over the disc 7, it strikes against the edge of the recess 9 and consequently turns the disc 7 in such a direction that the plates 3 and 4 of the talking head are moved away from one another. 95 This causes the disc 8 to be rotated in a sym- 100

metrical position (see Figure 4), by the coupling through the segments 11 and 12.

When the thickened part 1 reaches the recess 10 in the disc 8, which is now in the position shown in Figure 4, the disc 8 is rotated in the opposite direction and causes the disc 7 to be rotated in a backward direction so that now the plates 3 and 4 together with the magnets are moved back and the distance between the said plates is again normal.

I claim:

1. A reproducing magnet or talking head for telephones, capable of allowing the passage of riveted or welded thickened parts of wire, comprising movable jaws carrying the magnets of the telephone and having a funnel-shaped inlet end, in combination with means provided at the inlet and outlet end of the talking head for respectively positively opening and closing the said jaws under the control of the said thickened parts of wire.

2. A reproducing magnet or talking head for telephones capable of allowing the passage of riveted or welded thickened parts of wire comprising movable jaws carrying the magnets of the telephone and having a funnel-shaped inlet end, in combination with means for respectively positively opening and closing the said jaws under the control of the said thickened parts of wire, the said means comprising grooved guiding discs having recesses, screw-threaded journals mounted with the screw-threads running in opposite directions in the movable jaws on which the said guiding discs are mounted, and toothed segments secured to the screw-threaded journals and in toothed engagement with one another, as set forth.

40 In testimony whereof I have signed my name to this specification.

CURT STILLE.
